UNITED STATES PATENT OFFICE.

FRANK R. KRATZENBERG, OF NEW YORK, N. Y.

SASH-FASTENER.

No. 924,474.

Specification of Letters Patent.

Patented June 8, 1909.

Application filed September 14, 1908. Serial No. 452,821.

To all whom it may concern:

Be it known that I, FRANK R. KRATZENBERG, a citizen of the United States, and a resident of the borough of Bronx, county, city, and State of New York, have invented certain new and useful Improvements in Sash-Fasteners, as set forth in the following specification.

This invention relates to means for securing window sash, which means may be termed a sash-fastener.

An object of the invention is to improve the general construction of a sash-fastener; to provide a sash-fastener which is invisible from outside the window; to insure against the unfastening or picking of the fastener, as by burglars; and to provide such a means which is cheap, efficient and applicable to window sash with convenience and despatch. These and other objects of the invention will be clear from the following description and claims when read in connection with the accompanying drawings, which form part of this application, in which like characters indicate corresponding parts, and in which—

Figure 1 is an interior elevation of the top and bottom sash of a window construction, with parts broken away and showing the application thereto of the invention; Fig. 2 is a horizontal section on line II—II of Fig. 1; Fig. 3 is enlarged section through the vertical side rail of a top sash, showing the latch member in top plan; Fig. 4 is a front elevation of the latch member opened out so as to show its pattern; Fig. 5 is a top plan view of the coöperating combined stop and catch member; Fig. 6 is a sectional elevation through the parts shown in Fig. 5; Fig. 7 is a view corresponding to Fig. 5, but showing a modification; and Fig. 8 is a front elevation of the parts shown in Fig. 7.

Referring now more in detail to the drawings, 1 and 2 indicate respectively the top and bottom sash of a well known window construction, fitted to slide in the frame pieces 3 and 4.

5 and 6 indicate the vertical side rails of the top sash 1, the bottom rail of which is indicated by 7. The top rail of the bottom sash is indicated by 8 and the side rails by 9 and 10.

In Fig. 1 what may be termed a left handed embodiment of the invention is indicated by 11, while a right handed embodiment is indicated by 12. The right and left hand embodiments may be precisely similar and bear the

same relation to one another that right and left hands bear to each other, and are shown merely for purposes of illustration. While the left hand embodiment will be illustrated and described in detail, it is to be understood that the same details apply equally well to the right hand embodiment, as will be understood.

The latch member is shown most clearly in Fig. 4 and comprises a base plate 13, which may be suitably pierced to receive attaching screws 14. It is contemplated that the base plate 13 be secured to the inside face of one of the vertical rails of the top sash, as the rails 5 or 6. It may be secured so as not to be visible from outside the window, that is, so that the rail 5 completely conceals it from the exterior. A hinge 15 is provided along the side vertical edge of the plate 13 and the swinging latch plate 16 is secured along a corresponding vertical edge by the hinge 15 to the base plate 13. If desired, the latch plate 16 may have a curved offset lip 17, provided with a finger hold 18 projecting upwardly. It is to be understood, however, that the contour of the plates 13 and 16 may be modified at will, it being borne in mind that the axis of the hinge should be substantially vertical as indicated.

A coöperating member is provided for the latch member and may be designated as a combined stop and catch member, being shown in detail in Figs. 5-8 inclusive.

In Fig. 5 a metallic plate 19 is suitably pierced near its ends for the reception of securing means 20, and it is desirable that the plate have a reasonable degree of resilience, or at least that the catch member 21 have a certain degree of resilience or be yieldingly pressed upward into the position shown in Fig. 6, it being understood that for the purposes of this invention the catch tongue 21 is considered as yieldingly hinged to the plate 19. In the particular embodiment shown, the tongue 21 is cut out of the plate 19 and sprung upward into operative position as shown. A stop 22 may be conveniently formed also by striking up a portion of the plate 19, as indicated.

In Figs. 7 and 8, a modification of the combined stop and catch member is illustrated. In this modification, the plate 23 corresponds to the plate 19, but the yielding tongue 24 is located along one side of the plate 23, as shown, and may be formed by means of two cuts instead of three, as is nec-

essary in the previous embodiment. In this embodiment, a round-headed screw 25 may serve as a stop, although a stop similar to 22 may be provided if desired. It should also be understood that in the embodiment shown in Figs. 5 and 6, the stop 22 may be omitted as shown in Figs. 7 and 8, and the round-headed screw 25 substituted to serve as a stop.

- 10 As is well known in sash construction, a certain clearance is provided between the inside faces of the vertical side rails 5 and 6 in the top sash and the nearest edge of the top rail 8 of the bottom sash. It is within 15 this space that the latch member 13, 16 is to be situated. When in non-latching position, it is folded up as indicated in Figs. 2 and 3, so that the raising of the lower sash 2 may be effected at will, with the rail 8 easily clearing 20 the plate 16. To lock the sash the lip 17 or the finger hold 18 may be manually engaged to swing the plate 16 out into the position shown in Fig. 1. During this swinging movement, its lower edge 26 rides over and 25 depresses the catch 21 or the catch 24, as the case may be, the stop 22 or 25 limiting its swinging movement, whereupon the catch 21 or 24 springs up and serves as a stop to prevent the unlocking swing of the latch-plate. 30 To unlock the latch, a simple manual manipulation serves to depress the catch, and at the same time swing the latch plate from the position shown in Fig. 1 to the position shown in Figs. 2 and 3.
- 35 A window construction provided with a sash fastener of the type described would appear from the exterior to have no fastening whatsoever, and it is contemplated that it would be more than likely that any 40 tempted unwarranted entry through the window would be accompanied by considerable carelessness due to the apparently unsecured sash, and that this would result in the giving of an alarm to the occupants of an 45 apartment.

Although several embodiments of the invention have been illustrated and described,

it is to be understood that these are subject to modification and that the various features shown and described may be combined in 50 other combinations than those illustrated within the scope of the accompanying claims.

The sash fastener may be made satisfactorily and economically of sheet metal which may be stamped into form with convenience and despatch, although it is to be understood that other materials and modes of manufacture may be employed if desired.

What is claimed and what is desired to be secured by United States Letters Patent is:

1. In a sash fastener a swinging part to be hinged along a vertical edge to a vertical top sash rail; and a coöperating stop member to be secured to the top horizontal rail of the 65 bottom sash, said stop member comprising a catch for the said swinging part movable into and out of catching position.
2. In a sash-fastener a latch member comprising two plates hinged together along vertical edges; and a stop member comprising an engageable and disengageable catch.
3. In combination with window sash, a base plate secured to the inner face of a vertical rail of a top sash; a swinging latch plate 75 hinged along a vertical edge to said base plate; a combined stop and catch member secured to the top rail of the bottom sash to coöperate with said latch plate, the catch of said combined member being movable into 80 and out of catching position.
4. A sash-fastener comprising a latch member having a flat sheet metal base plate and a sheet metal latch plate hinged together; and a coöperating catch member 85 having a sheet metal base plate and an integral upturned depressible catch.

In testimony whereof, I have signed my name to this specification, in the presence of two subscribing witnesses.

FRANK R. KRATZENBERG.
